(57) **CLAIM**

I claim the ornamental design for a baby plate, as shown and described.

DESCRIPTION

FIG. 1 is a top-side perspective view of a baby plate; FIG. 2 is a top view of the baby plate of FIG. 1; FIG. 3 is a left side view of the baby plate of FIG. 1; FIG. 4 is a front side view of the baby plate of FIG. 1; FIG. 5 is a right side view of the baby plate of FIG. 1; FIG. 6 is a rear side view of the baby plate of FIG. 1; and, FIG. 7 is a bottom view of the baby plate of FIG. 1. The broken lines in the drawings illustrate portions of the baby plate that form no part of the claimed design.
